UNITED STATES PATENT OFFICE.

OTTO A. HECKEL, OF ST. LOUIS, MISSOURI.

DOOR-HANGER.

1,115,816.

Specification of Letters Patent.

Patented Nov. 3, 1914.

Application filed August 9, 1913. Serial No. 783,874.

To all whom it may concern:

Be it known that I, OTTO A. HECKEL, a citizen of the United States, and resident of St. Louis, Missouri, have invented certain new and useful Improvements in Door-Hangers, of which the following is a specification.

This invention relates to improvements in door hangers, and has for its object a track 10 swingingly mounted, and a means whereby either end of said track and center portion can be either elevated or lowered so as to properly place the door in alinement with the door casing or meeting door.

15 A further object is to provide in addition to the track suitable adjustable roller brackets by which the door is suspended to the track.

The essential feature is to provide the 20 hanger with a mechanism by which the hidden incased end of the track can be adjusted vertically by manipulation from the portion over the door opening.

Figure 1 is a side elevation of my complete invention showing the door in position on the track. Fig. 2 is a cross-sectional view of the overhead pocket showing the track and door in end view. Fig. 3 is a side elevation of the track with parts broken away 30 showing the operating mechanism. Fig. 4 is an end view of the suspension bracket by which the track is supported; a portion of the same being in section showing the adjusting screw. Fig. 5 is a side view of the 35 same. Fig. 6 is a sectional view of a portion of the meeting tracks showing their connection. Fig. 7 is a perspective view of the bracket bar by which the rails are supported. Fig. 8 is a sectional view of the 40 operating mechanism by which the gears are manipulated. Fig. 9 is a sectional view of the adjustable roller bracket for supporting the door to the track. Fig. 10 is a sectional view of a hanger showing the construction 45 when one track or rail is used. Fig. 11 is a bottom plan view of a portion of the single rail. Fig. 12 is a sectional view of a modified form of hollow rail showing the internal ball roller. Fig. 13 is a longitudinal sectional view of the same. Fig. 14 is a cross-sectional view of the same when used as a 50 single rail. Fig. 15 is a cross-sectional view

of an additional modified form of track. Fig. 16 is a side elevation of a portion of said track showing the connection of the 55 meeting ends.

In the construction of my invention I provide a track 17 consisting of rails 18 and 19, the butting ends connected together by a plug 20 at a point indicated by the numeral 21, these rails as shown are preferably arranged two in number and are separated and supported by bracket bars 22; these bars having projecting trunnions 23 which pass through openings formed in the 65 rails; in this instance the rails are tubular in form.

The bracket bars are provided with central perforations 24 in which are located internally screw-threaded nuts 25, these nuts 70 being designed to be screwed to the screw threaded hanger rod 26, the upper end of which being preferably bent at right angles and held in a bearing 27 which is firmly secured to the header 28 which forms the upper portion of the hanger pocket formed above the door; this arrangement is such that the hanger rod together with all the mechanism supported thereby can swing to 75 keep the track in perfect horizontal position. 80

The heads of the nuts 25 are suitably slotted for the insertion of a screw driver so that the nut can be properly adjusted on the threaded portion of the hanger rods for 85 raising and lowering the position of the track.

In Fig. 1 I show a track of its complete length in relative position with the door supported thereon; in this instance the track 90 is divided into two sections and connected at the point indicated by the numeral 21; at two ends of the section 18 are located bracket bars supporting a bevel-gear mechanism by which the rear end of the track 95 can be manipulated from the front or door opening; this operating mechanism consists of a horizontal shaft 29 supported in suitable bearings 3, 31, and 32, the bearing 30 secured to the bracket bar as shown in 100 Fig. 3, the bracket 32 being secured to a projection 33 mounted on the one side of the front bracket bar and in this projection is supported a stud 34 having a slotted head

35 at its bottom and a bevel-gear 36 at the top; this bevel-gear meshing with a bevel gear 37 formed on the front end of the shaft 29; the opposite end of said shaft is 5 provided with a bevel-gear 38 which meshes with a bevel-gear 39 formed on a stud located in the rear bracket bar, the said stud being internally screw-threaded and operating on the threaded hanger rod; the object 10 of this mechanism is that if in the event the rear end of the track should become out of alinement and since that portion of the track being entirely incased in the wall, by the manipulation of the stud 34, the rear 15 concealed end of the track can be raised or lowered so as to bring the door 40 in proper alinement with the casing.

The front hanger bar which is also provided with an internally screw-threaded nut 20 41 can be manipulated so as to raise or lower that portion of the track in accordance with the hanging portion of the front edge of the door. To the ends of the section 18 of the track is connected the section 19, its opposite or front end supported to a hanger rod 42, likewise provided with an internally screw-threaded nut 43 which can be operated likewise to raise or lower the end of the section 19; this entire mechanism is 25 concealed in an overhead pocket 44 formed in the wall and is hid from view in the door opening by means of the moldings or guide strips 45 but access can be had to the internally screw-threaded nuts by inserting a 30 screw-driver through the door opening between the strips 45 and the entire track placed in proper alinement so as to level the door 40 to have its edges meet in proper 35 alinement with the door frame or meeting door.

The door 40 is supported on the track by 40 roller hangers 44' and consists of a bracket 45' firmly secured to the upper edge of the door, and between the bracket and the door is located a nut 46 having internal 45 screw-threads and operating on a screw-threaded stud 47 carried by the plate 48 which has radially projecting arms 49 bent upwardly and over the rails and in the bent 50 portion are located rollers 50; the plate is also provided with two guide pins 51 which extend downwardly through the bracket 45' and into recesses 52 bored into the top of the door; the object of these guide pins is to hold the roller hanger in rigid position yet allow 55 for the adjustment vertically by the movement of the nut 46; the purpose of this adjustment is that after the door has been hung upon the rails the bottom edge of the door can be properly spaced from the floor.

As shown in Fig. 7 this bracket bar is the one used in between the front and rear bracket bars for supporting the shaft 31

which is necessary where the space between the two end bracket bars is at a great length. 65

In Fig. 10 I show a like construction to that just described but where only a single hollow tubular track is used and suspended direct upon the hanger rods I use rollers 53 of a construction as that shown in Fig. 12; 70 these rollers operating on the inside of the hollow tubes, the bottom edge of said tubes being split and access being had to the adjusting screws by inserting a screw-driver through the apertures 54 (see Fig. 10 and 75 11). If found desirable I may also use a structure of track and roller hanger as that found in Fig. 15, providing in this instance wood rails 54' and connected together by the cross-bar 55.

Having fully described my invention what I claim is:

1. A door hanger comprising a sectional track, adjustable swinging brackets supporting the track, and an adjusting means for 85 alining the incased section of the track for properly placing the door in alinement with the casing.

2. A door hanger comprising a suspended track, adjustable swinging brackets carrying the same, adjusting means carried by the brackets for regulating the position of the track, and a suspending means whereby 90 the door is suspended to the track.

3. A door hanger comprising a swinging 95 supported sectional track and a gear mechanism whereby the inner end of the concealed section of the track can be raised and lowered by manipulating a screw located above the door opening in combination with adjusting means for lining up the track on the 100 swinging hangers.

4. A door hanger comprising a suspended swinging sectional track, brackets for supporting the same to the header, a combined 105 screw and gear mechanism whereby either section of said track can be raised or lowered from above the door opening to properly line up said track, and adjustable roller brackets carrying the door.

5. A door hanger comprising a track suspended from a header, swinging brackets supporting said track, internally screw threaded screws carried by the brackets whereby the track can be elevated or lowered, a beveled gear mechanism carried by the brackets by which the inner end of said track is manipulated from the free forward end and adjustable roller brackets supporting the door upon the track. 115

6. A door hanger of the class described comprising a sectional track, screw threaded hanger rods swingingly mounted to the header of the door frame work for supporting the sectional track; a beveled gear mechanism carried by one section of the sec- 120

tional track by which the inner end of said track may be raised and lowered by manipulating the mechanism at the front end of said section, and internally screw threaded screws operated on the hanger rods for adjusting the opposite end of the inner section and one end of the outer section, substantially as specified.

In testimony whereof, I have signed my name to this specification, in presence of two 10 subscribing witnesses.

OTTO A. HECKEL.
